RECORD-CHANGING DEVICE FOR
TALKING MACHINES

Louis Thévenaz, Les Rasses, near Sainte Croix,
Switzerland, assignor to Hermann Thorens So-
ciété Anonyme, Sainte Croix, Switzerland, a
firm of Switzerland

Application May 17, 1945, Serial No. 594,340
In Switzerland July 11, 1944

5 Claims. (CL. 274—10)

1

At the termination of the playing of a record by the tone arm, the needle enters the final groove of increasing pitch which imparts to the tone arm the sudden swing necessary to engage with the motor the control mechanism of the record-changing cycle; the term "cycle" will designate in the following specification and claims, the whole of the operations of the record-changing and tone arm mechanism which are necessary to bring a record and the tone arm into playing position, in which position this mechanism is disengaged again from the motor. This cycle comprises in the present case the following movements: the tone arm is first raised above the record which has been played and then displaced towards the outside of the turntable; the push member of the record supporting spindle is then actuated and the lower-most record of the stack drops into the turntable; the pick-up is then brought back inwardly and after having resumed its position over the first groove of the record, it is lowered to engage the record.

This cycle is of a relatively short duration with respect to the playing duration of a record, generally of a few seconds only; there are known so-called "pause" devices adapted to increase this duration. Those devices stop up the cycle during a certain lapse of time by completely disengaging its control member from the motor during this whole lapse of time.

This invention relates to a record-changing device with pause mechanism. According to a feature of the invention a speed change gear is provided between the motor and the cycle control member, this speed change gear being adapted to change automatically the duration of the cycle by running a part at least of this cycle at a reduced mean speed.

The speed change gear may be of the toothed or of the friction type; it may intervene at any desired part of the cycle, for instance at the beginning thereof, during the outward back movement of the pick-up; it may be a single or a multiple speed change gear; it may be combined with a device enabling it to be put out of service at any moment before or during its operation.

The annexed drawing represents, by way of example, one convenient construction of a record-changing device with pause mechanism embodying the invention, wherein only the members necessary to the understanding of the invention are shown. In this embodiment, a reduced mean speed is obtained on a fraction

2

of the cycle by means of a speed reducing gear and a step by step mechanism.

Fig. 1 is a plan view thereof, the turntable being removed;

5 Fig. 2 is a section through the broken line II—II of Fig. 1;

Fig. 3 is a plan view similar to Fig. 1 in a different position, and

10 Fig. 4 is a section similar to Fig. 2 in the position of Fig. 3.

In the drawing, 1 and 2 designate the upper and lower plates of the frame supporting the pause mechanism; 3 is the driving shaft of the turntable and 4 the spindle of the multiple cam

15 5 which constitutes the control member of the cycle; this control member is held idle while a face of a record is being played but it is actuated by the driving shaft 3 from the termination of this playing to the beginning of the playing of the following record face by a toothed transmission gear adapted for automatic engagement and disengagement.

On the driving shaft 3 is secured a toothed pinion 6. On the spindle 4 of the cam 5 are 25 mounted two gears 7 and 8 of equal large diameter, arranged in closed superposition. The upper gear 7 is secured on the spindle 4 while the lower gear 8 runs loose on this spindle. The upper gear 7 is provided with a toothed sector 30 7' raised by flanging onto a higher plane than the remainder of its toothing. 9 designates a lever pivoted about a pin 10 fastened to the upper plate 1 against the lower face of which the lever 9 is arranged. The lever 9 carries on

35 its lower face a pin 11 about which runs loosely a reversing pinion 12 whose toothing has a pitch corresponding to the pitches of the gears 7 and 8 and of the pinion 6 and a sufficient thickness to enable it to simultaneously mesh with both the gears 7 and 8, but for the length of the raised sector 7' of the upper gear 7. The lever 9 carries further, on its upper face, a pin 13 adapted to co-operate through a hole 28 of the plate 1 with a stop surface 14' of a bell crank 14

40 pivoted about a pin 15 fastened to the upper plate 1, against the action of a restoring spring 16. The lever 9 is swingingly arranged so that its reversing pinion 12 meshes constantly with the gears 7 and 8 and may be engaged with or 45 disengaged from the pinion 6 according to the position of the bell crank 14. When the pinion 12 meshes with the pinion 6, the movement of the driving shaft 3 is transmitted at 50 the reduced speed by the gears 7 and 8 to the cam 5

which controls the cycle of the record-changing device.

17 is a further toothed pinion whose pitch corresponds to the pitch of the gears 7 and 8 with which it may simultaneously mesh. This pinion 17 is secured on a pin 18 pivoted in the plates 1 and 2 and adapted to axially slide so that the pinion 17 is enabled to mesh either simultaneously with both the gears 7 and 8 or only with the upper gear 7. The lower end of the pin 18 rests on a cup-shaped portion 19 of a bell crank 20 pivoted about a pin 29 and connected through a link 21 hinged on the pins 31 and 32 with a crank arm 30 carrying a control knob 22. Owing to the inclined plane of the cup 19, the pinion 17 may be raised by the bell crank 20 against the action of a spring 23 held against the upper end of the pin 18. In its normal position shown in Fig. 4, the pinion 17 meshes with both the gears 7 and 8; on the contrary, in the position of Fig. 2, the pin 18 is raised by the bell crank 20 and the pinion 17 does no more mesh with the loose running lower gear 8. On the pin 18 is further secured, below the pinion 17, a star wheel 24 adapted to co-operate, in the raised position of the pin 18 (Fig. 2) with a resilient pawl 25 fastened to the lower face of the loose running lower gear 8.

The upper gear 7 carries on its upper face a pin 26 adapted to co-operate, at each complete revolution of this gear driven with the cam 5, with a pin 27 carried by the lever 9 to disengage the pinion 12 from the driving pinion 6 as shown in Fig. 3.

The operation of the mechanism described and shown is as follows: During the playing of a record face, the bell crank 14 holds, by its stop surface 14' co-operating with the pin 13, the lever 9 in the position shown in Fig. 3 in which the reversing pinion 12, which is in constant gearing relation with the gears 7 and 8, does not mesh with the driving pinion 6. The multiple cam 5 dependent in rotation upon the gear 7 remains thus idle. At the termination of the playing, the sudden inward swing imparted to the tone arm by the final groove of the record causes, by means of a known automatic stopping device (not shown), the anti-clockwise rotation of the bell crank 14 which releases the pin 13; the lever 9, actuated by the spring 16 is brought into the position of Fig. 1 in which the reversing pinion 12 meshes with the driving pinion 6. The movement of the pinion 6 is thus transmitted to the upper gear 7 and through the latter to the cam 5 which controls the cycle of the record-changing device. This cycle is performed during one whole revolution of the cam 5. The duration of this complete revolution of the cam is determined by the gear ratio between the driving pinion 6 and the gear 7. This duration is normal when the pause mechanism controlled by the knob 22 is not in action, that is when the movement of the driving pinion 6 is transmitted directly through the pinion 12 to the upper gear 7. Even when the axially immovable reversing pinion 12 fronts the elevated toothed sector 7' of the gear 7 with which it cannot mesh, the movement is transmitted at the same speed through the loose running lower gear 8 and the pinion 17 which meshes simultaneously with both the gears 7 and 8. The whole operates as if the gears 7 and 8 would constitute a single gear with continuous toothing secured on the spindle 4 of the cam 5.

If, however, the pause mechanism is put in

action by turning the knob 22 in an anticlockwise direction, the members of the mechanism take up, when the pinion 12 is brought in front of the toothed sector 7', the position shown in the Figs. 1 and 2. The bell crank 20 is turned in a clockwise direction under the action of the link 21 and raises by means of the inclined surface of its cup 19 the pin 18 which carries the pinion 17 and the star wheel 24. The pinion 17 does no longer mesh with the lower gear 8, but the star wheel 24 is brought into the path of the outer end of the resilient pawl 25 which is fastened to this lower gear 8. At every revolution of the gear 8, which meshes alone with the reversing pinion 12, the pin 18 is turned one step and moves through a corresponding angular value the upper gear 7 which meshes with the pinion 17 but not with the pinion 12. Thus, while the elevated toothed sector 7' fronts the pinion 12, the movement of this latter is transmitted step by step through the gear 8, the pawl 25, the star wheel 24, the pinion 17 and the gear 7 to the cam 5 which controls the cycle. The cycle is thus not stopped at all but proceeds at a reduced mean speed for a predetermined angular displacement of the spindle 4 of the cam 5.

As an alternative, for disengaging the upper gear 7 from the pinion 12, a sector 7' without toothing may be provided; however, the construction described above and shown in the drawings presents the advantage that as the second pinion 17 constantly meshes with the gear 7, even in front of the elevated toothed sector 7', any danger of canting of the pinion 17 with the end of a toothless sector is avoided.

Also in order to avoid its canting with the star wheel 24, the pawl 25 is a leaf spring.

In order to stop the slow running of the cycle when the sector 7' faces the pinion 12, it will be sufficient to turn the knob 22 in a clockwise direction, whereby the pin 18 and its pinion 17 will be lowered; this latter meshes thus once more with the lower gear 8 and rotates the upper gear 7 at the normal speed of the cycle.

The fraction of the cycle which is to be run at a reduced mean speed in order to obtain a pause of definitive duration may be chosen at will; it depends upon the situation of the sector 7' with respect to the cam. In the construction described and shown, the sector 7' is arranged so that the slackening of the cycle occurs from the termination of the raising movement of the pick-up over the record which has been played and during the outward displacement of the pick-up. One avoids in this manner that the pause occurs before playing of the first record after starting of the changing device; this peculiar arrangement permits also, during the pause, to put into action a repetition device of the record which has been played, what would not be possible if the pause would become effective after the movements controlling the dropping on the turntable of the following record.

It will be understood that the reversing pinion 12 is arranged so that when a mechanical strain is applied onto the cam 5, this pinion tends to lean more firmly against the driving pinion 6, whereby any untimely releasing is avoided.

The duration of the pause may be changed according to the length of the sector 7', the arm number of the star wheel 24 or the number of the pawls 25. A pause device with several speeds may also be provided, for instance by securing on the sliding pin 18 a plurality of

superposed star wheels having each a different number of arms.

What I claim is:

1. In a talking machine with record changing device of the kind having a mechanism for driving from a continuously rotating element a main shaft adapted to rotate through a predetermined angle for each record changing operation and having two coupling members, the first being part of the continuously rotating element, the second being brought into engagement with the first one at the end of each audition of a record face and remaining engaged therewith until, at the end of the process of record changing and for a predetermined angular position of the main shaft, disengaging means are brought into action, in combination, a first speed reducing gear between said second coupling member and said main shaft to drive the latter at a first determined speed, a second speed reducing gear between the same elements to drive said main shaft, during a part at least of its angular displacement, at a mean speed substantially smaller than said first speed, means controlled by said main shaft to successively put into action said first and second speed reducing gears during the record changing process and for predetermined angular positions of said main shaft, manually operable means being provided for rendering said second mentioned gear inoperative and to drive said main shaft at the first determined speed during the whole process of record changing.

2. In a talking machine with record changing device of the kind having a mechanism for driving from a continuously rotating element a main shaft adapted to rotate through a predetermined angle for each record changing operation and having two coupling members, the first being part of the continuously rotating element, the second being brought into engagement with the first one at the end of each audition of a record face and remaining engaged therewith until, at the end of the process of record changing and for a predetermined angular position of the main shaft, disengaging means are brought into action, in combination, a first speed reducing gear between said second coupling member and said main shaft to drive the latter at a first determined speed, a second speed reducing gear between the same elements to drive said main shaft, during a part at least of its angular displacement, at a mean speed substantially smaller than said first speed, means controlled by said main shaft to drive it during a definite angular displacement through the first mentioned speed reducing gear and during another definite angular displacement through the second mentioned speed reducing gear, manually operable means being provided for rendering said second mentioned gear inoperative and to drive said main shaft through said first mentioned speed reducing gear during the whole angular displacement of the main shaft controlling the process of record changing.

3. In a talking machine with record changing device of the kind having a mechanism for driving from a continuously rotating element a main shaft adapted to rotate through a predetermined

angle for each record changing operation and having two coupling members, the first being a pinion secured to the continuously rotating element, the second being a reversing pinion adapted to be brought into meshing engagement with said first mentioned pinion at the end of each audition of a record face and remaining engaged until, at the end of the process of record changing and for a predetermined angular position of the main shaft, disengaging means are brought into action, in combination, a first gear loosely mounted on the main shaft and constantly meshing with the reversing pinion, a second gear fixedly secured on the main shaft, first means for driving said second gear from said first gear at the same speed, second means for driving said second gear from said first gear through a predetermined angular displacement at a mean speed substantially smaller, third means automatically controlling the first and second mentioned means to put them successively into action for predetermined angular positions of the main shaft and manually operable means for rendering said third means inoperative, the first mentioned means then remaining in action during the whole process of record changing.

4. In a talking machine with record changing device, in combination a main shaft adapted to rotate through a predetermined angle for each record changing operation, a first gear loosely mounted on said main shaft, a second gear equal in diameter fixed on said main shaft over said first gear and having a toothed sector raised above the general plane of the toothing, a reversing pinion automatically coupling said first gear with a continuously rotating element at the end of each audition of a record face, said reversing pinion meshing also with said second gear but when facing said raised toothed sector thereof, a sliding pinion adapted to mesh either simultaneously with both said first and second gears or with said second gear only, a star wheel dependent upon said sliding pinion, at least one pawl fastened to said first gear for driving said star wheel through at least one step at every revolution of said first gear when said sliding pinion is in said second meshing position, and manually operable control means for displacing said sliding pinion into said second meshing position to cause the cycle control cam to be driven at reduced mean speed when said reversing pinion fronts the raised toothed sector of said second gear.

5. In a talking machine with record changer, the combination as claimed in claim 4 wherein the manually operable control means for displacing the sliding pinion comprises a bell crank having an inclined plane cooperating with the end of the shaft of said pinion.
